(57) **CLAIM**

USPC **D8/4**

The ornamental design for scissors as shown and described.

DESCRIPTION

(58) **Field of Classification Search**

FIG. 1 is a perspective view of scissors showing my new design;

USPC D8/4, 5, 6, 7, 9, 14, 51, 52, 54, 55, 57,

FIG. 2 is another perspective view thereof;

D8/58, 61, 67, 69, 93, 98, 499; D15/127,

FIG. 3 is a front elevational view thereof;

D15/129, 139; D21/532

FIG. 4 is a rear elevational view thereof;

CPC ... A01G 2/35; A01G 3/00; A01G 3/02; A01G

FIG. 5 is a left side elevational view thereof;

3/04; A01G 3/06; A01G 3/08; A01G

FIG. 6 is a right side elevational view thereof;

3/002; A01G 3/021; A01G 3/025; A01G

FIG. 7 is a top plan view thereof;

3/065; A01G 3/067; A01G 3/081; A01G

FIG. 8 is a bottom plan view thereof; and,

2003/005; A01G 2003/007; A01G 3/0475;

(Continued)

A01G 3/053; A61F 15/02; B26B 13/00;

B26B 13/005; B26B 13/02; B26B 13/04;

B26B 13/06; B26B 13/16; B26B 15/00;

B26B 15/02; B26B 15/001; B26B 17/00;

B26B 17/003; B26B 17/006; B26B 17/02;

FIG. 9 is a perspective view of the scissors where the scissors are in a configuration of use.

The broken lines in the drawings depict portions of the scissors that form no part of the claimed design.

1 Claim, 9 Drawing Sheets
